UNITED STATES PATENT OFFICE.

NEWTON L. BARGER AND JAMES H. FORD, OF BRAEHOME, WEST VIRGINIA.

COAL-LOADING MACHINE.

Application filed March 17, 1921. Serial No. 453,005.

To all whom it may concern:

Be it known that we, NEWTON L. BARGER and JAMES H. FORD, citizens of the United States, residing at Braeholm, in the county 5 of Logan, State of West Virginia, have invented certain new and useful Improvements in Coal-Loading Machines; and we do hereby declare the following to be a full, clear, and exact description of the invention, 10 such as will enable others skilled in the art to which it appertains to make and use the same.

The object of the invention is to provide simple and efficient means of a character 15 adapted to be readily handled or directed and positioned in a mine for loading coal cars from the pile of loose material on the mine floor after a heading has been loosened and displaced by blasting or through the 20 operation of cutting or picking machines, to avoid the inconvenience, loss of time and labor incident to the shoveling or the manual lifting of the lumps of coal from the pile to the cars; and more particularly to provide 25 an apparatus for the purpose indicated which will be essentially self-feeding or supplying to act as a feeder for a conveyer by which the material may be conducted to a conveniently located car or like receptacle, 30 to the end that the manual effort incident to car filling may be minimized if not eliminated; and more especially to provide a conveyer feeding shoe adapted to be positioned against or in contact with the side of a pile 35 of loose material just as it falls from the blasted header or wall of the mine lead or room, to draw the material away from the pile and deposit it upon the conveyer under such conditions as to avoid the unnecessary 40 breaking or powdering of the coal even when the latter is of the bituminous variety, so as to avoid the unnecessary reduction of the commercial value of the product; and with these general objects in view the invention 45 consists in the construction, combination and relation of parts of which a preferred embodiment is shown in the accompanying drawing wherein:

Figure 1 is a side view of a coal mine car 50 loading apparatus embodying the invention.

Figure 2 is a plan view of the same.

Figure 3 is a front view of the machine.

Figure 4 is a detail sectional view of a 55 portion of the upper or driving roller of

the shoe on the plane indicated by the line 4-4 of Figure 2.

Figure 5 is a detail horizontal sectional view of the mounting of the forward or pick-up roller of the shoe on the plane indicated by the line 5-5 of Figure 3. 60

Figure 6 is a detail vertical section of the pick-up roller at the forward end of the shoe on the plane indicated by the line 6-6 of Figure 3. 65

Figure 7 is a detail side view partly in section of one of the tooth carrying links of the pick-up carrier.

Figure 8 is a detail in perspective of one 70 of the tooth carrying links.

The apparatus consists essentially of a conveyer 10 preferably comprising relatively movable members 10^a and 10^b pivotally jointed at 11 to permit of angular adjustment of the delivery member 10^a upon an 75 axis represented by the pivot 11 which consists in the construction illustrated of a transverse shaft through which motion may be conveyed to a continuous belt or apron 12 which traverses the full length of the conveyer to discharge material conducted thereby into a delivery chute 13 for discharging to a mine car indicated fragmentarily at 14; with which conveyer is associated a feeding shoe 15 disposed at the receiving end of the conveyer, and preferably at one side of the latter, and serving as a means for picking up or withdrawing the lumps or fragments of coal from the pile on the floor of the mine to deposit it upon the 80 receiving end of the conveyer. 85

As shown, the apron or belt 12 of the conveyer, which may be provided with transverse slats or flights 16 intermediately traverses a drum 17 carried by the shaft 11 95 which receives motion from a motor 18 through a counter shaft 19 and a chain and sprocket gearing 20, a sprocket wheel 21 being fitted upon one end of the shaft 11. The remote ends of the conveyer apron traverse rollers 22 and 23 at the free ends of the conveyer sections 10^a and 10^b, while the delivery chute 13 is pivotally mounted as at 24 upon the angularly adjustable member 10^a of the conveyer to adapt itself to the position and height of the car 14 relative to the delivery end of the conveyer which is positioned by means of a strut or brace 25 consisting of the telescoping members 26 and 27 with a feed nut 28 engaging a 100 105 110

threaded portion of the member 26 and having a hand wheel or grip 29 to facilitate the manual adjustment thereof. The remote extremities of the brace or strut are pivoted 5 at 30 and 31 respectively to the movable member of the conveyer and the main frame 32 of the apparatus which main frame may be constructed to form a housing as indicated to enclose the motor 18 and thus protect 10 the operating mechanism from the dust and particles of coal which may be dropped from the conveyer.

The feeding shoe is of general triangular shape, viewed in vertical longitudinal section or in end view as indicated in Figure 3 with its elevated inner delivery end overhanging the receiving end of the conveyer, and with its nose or receiving end reduced and located close to the plane of the floor 20 or supporting surface so as to provide for forcing the same into close contact with the side of a pile of material to be transferred, and in such relation to the pile as to cause the material thereof to be readily 25 drawn from the pile to an endless carrier 33 with which the shoe is equipped and which is provided with hook shaped teeth 34 having forwardly presented concave faces 35 adapted to pass under the lumps of 30 coal in the pile and draw them from and upon the inwardly moving upper surface or run of the carrier for transfer thereby to the receiving end of the conveyer.

In the construction illustrated the carrier 33 at the upper inner end of the shoe, of 35 which the upper surface is abruptly inclined to facilitate arrangement in close relation with the pile of material, traverses a roller 36, receiving motion through a sprocket 40 chain 37 traversing sprocket wheels 38 and 40 39 from a counter shaft 40 which extends longitudinally of the frame of the conveyer and is driven by the motor 18 through the sprocket gearing 41, to the end that there 45 is a timed relation between the operations of the shoe carrier and the conveyer belt or apron, so that the material may not be deposited by the feeding shoe upon the receiving end of the conveyer more rapidly 50 than the same can be conducted by the conveyer to the car.

At the pick-up or feed end of the shoe the carrier 33 extends around a pick-up roller 42 of which the shaft or spindle 43 is preferably mounted in adjustable bearing blocks 44 fitted in horizontal guides 45 and engaged by adjusting bolts 46 designed to maintain a proper tension of the carrier to insure an effective engagement of the 55 teeth 34 with the loose material in the pile which is being attacked. The carrier preferably consists of a plurality of parallel chains 33^a each comprising a series of links shown in detail in Figures 7 and 8 and particularly designated at 33^b, and these links,

or as many of them as may be preferred carry the hook shaped teeth 34, constructed as above indicated and detachably or replaceably secured to the links by having threaded stems 34^a engaged by nuts 34^b or the equivalent thereof. These teeth are preferably interchangeable or replaceable to provide for renewal in the event of breakage or when dulled by contact with the coal to an extent sufficient to interfere with the proper and effective engagement of the coal in the operation of drawing the lumps thereof from the pile to the upper inwardly moving surface of the carrier for transfer as above indicated to the feed end of the 75 conveyer.

The elements of the shoe including the suitably braced frame 47 thereof and the carrier is such that the teeth 34 at the forward or nose end of the feeder, in passing 80 around the pick-up roller 42 terminally sweep close to the surface of the mine floor and thence swing around under the lumps of coal adjacent to the nose end of the feeder to tilt or draw the lumps upon the carrier 85 with the least possible jar or blow and hence with the minimum tendency to cause breakage or fracture of the lumps, to the end that the pulverizing or powdering of the material or the breakage thereof into small 90 particles may be minimized to maintain the highest possible commercial standard of the product; and to the same end there is provided at the elevated discharge or delivery 95 end of the feeder, an inwardly and downwardly inclined fender 48, consisting for example of a plurality of bars or strips of which the lower extremities overlap or overhang the lower portion of the conveyer belt or apron 12 for the purpose of conducting 100 the lumps of coal from the feeder to the receiving end of the conveyer and to ease or modify its deposit thereupon to avoid 105 objectionable breakage or pulverizing of the lumps. A guard 49 may be also arranged at 110 the opposite side of the receiving end of the conveyer to prevent the lumps from rolling beyond the zone of the conveyer belt or apron.

What is claimed is:

1. A mine car loading apparatus having a conveyer mechanism provided with a feeding shoe, of generally triangular form, the reduced end adapted for disposition in contact with the side of a pile of loose material to be loaded, and having means for drawing the material from the pile and conducting it to the conveyor, said means including an endless carrier consisting of a plurality of parallel tooth carrying chains of which certain of the links are provided with openings to receive therein the stems of the said teeth.

2. A mine car loading apparatus having a conveyer mechanism provided with a feeding shoe, of generally triangular form, the

nose end of which is adapted for disposition in contact with the side of a pile of loose material to be loaded, and having means for drawing the material from the pile and conducting it to the conveyer, said means including an endless tooth carrying chain disposed intermediate the sides of said feeding shoe and transversing in a path parallel with the inclined side thereof, the upper 10 faces of the inclined sides of the feeding shoe being in alignment with the tops of said teeth.

3. A mine car loading apparatus having a conveyer mechanism provided with a feeding shoe extending laterally therefrom and secured thereto, said feeding shoe being of triangular form and having its nose end adapted for disposition in contact with the side of a pile of loose material to be loaded, 15 means for drawing the material from the pile and conducting it to the conveyer, said means including an endless carrier consisting of a plurality of parallel tooth carrying chains of which certain of the links are provided with vertical openings to receive therein the threaded stems of the said teeth, and means located within the nose end of the feeding shoe and extending exteriorly thereof, for adjusting the said carrier.

20 4. A mine car loading apparatus having a conveyer mechanism provided with a feeding shoe extending laterally therefrom and secured thereto, said feeding shoe being of generally triangular form and having its 25 nose end adapted for disposition in contact with the side of a pile of loose material to

be loaded, means for drawing the material from the pile and conducting it to the conveyer, said means including an endless carrier consisting of a plurality of parallel 40 tooth carrying chains of which certain of the links are formed with aligned countersinks in their top and bottom faces, said countersinks being connected by a bore of smaller diameter, and the said teeth being 45 provided with threaded stems, the lower portions of the teeth being receivable in the countersink in the top face, the threaded stem passing through the bore into the countersink in the bottom face, and a nut 50 threaded upon the stem and seated within the bottom countersink.

5. A mine car loading apparatus having a conveyor mechanism provided with a feeding shoe of generally triangular form, the 55 reduced end adapted for disposition in contact with the side of a pile of loose material to be loaded, and having means for drawing the material from the pile and conducting it to the conveyor, said means including an 60 endless carrier consisting of a plurality of parallel tooth carrying chains of which certain of the links are provided with countersunken openings to receive therein the stems and the lower portions of the said teeth. 65

In testimony whereof, we affix our signatures, in the presence of two witnesses.

NEWTON L. BARGER.

JAMES H. FORD.
